UNITED STATES PATENT OFFICE.

GEORGE F. COATES, OF RUTHERFORD, NEW JERSEY.

DEVICE TO BE USED IN MONOTYPE-MACHINES.

1,011,581.

Specification of Letters Patent. Patented Dec. 12, 1911.

Application filed January 14, 1911. Serial No. 602,594.

To all whom it may concern:

Be it known that I, GEORGE F. COATES, a citizen of the United States, and a resident of Rutherford, county of Bergen, and State of New Jersey, have invented a new and useful Device to be Used in Monotype-Machines, of which the following is a full, clear, and exact specification.

My invention is for use solely in the machine for preparing the ribbon which is intended for use in the casting machine, and its object is the devising of means whereby the paper nibs, punched from the ribbon in the process of perforating it, may be removed in the least possible time from the chamber provided for collecting them and transferred to the receptacle forming a part of my device, the removal of the nibs being accomplished by means of pneumatic power.

Referring to the drawings forming part of this specification, Figure 1 is a sectional elevational view of my nib extractor in position upon the ribbon perforating machine shown in fragmental sectional elevation. Fig. 2 is a sectional view through the line $x-x$ of Fig. 1 showing additional parts of the perforating machine. Fig. 3 is a full size view of my device looking upward from the bottom, and Fig. 4 is a full size view of the lower part shown in Fig. 1.

The monotype casting machine includes two distinct machines, namely, the casting machine proper, and the machine for preparing the perforated ribbon used in the casting machine.

The casting machine is mainly controlled by a continuously traveling perforated ribbon. The perforations in the ribbon effect an operation of pneumatically controlled mechanisms which accomplish the desired ultimate results above enumerated.

The ribbon preparing machine is for the purpose of perforating the ribbon in a manner such that when it is used with the casting machine the desired matter will be cast.

My invention has only to do with the ribbon preparing machine.

The machine has a keyboard which is operated much as a typewriter. The depressing of the keys effect a raising and lowering of a series of perforating or punching needles which, as they are forced upward, perforate the ribbon passing in front of them. The needles are positioned in a row transversely of the ribbon, and puncture it in a correspondingly transverse direction.

Only sufficient of the ribbon preparing (or keyboard) machine is shown in the accompanying drawings to clearly understand the purpose of my invention and the manner of using it.

The ribbon 1 is made of paper wound in a roll 2 and has along each of its edges a row of perforations 3. The paper roll is mounted on a shaft 4 and is fed therefrom to a spool 5. The intermediate strip of ribbon between the roll and spool moves around the lower side of a stationary cylinder 6. The cylinder is hollow to afford a chamber 7 through which extends a shaft 8 having ends projecting through the ends of the cylinder. On these ends are mounted spur wheels 9 provided with the peripheral spurs or pins 10. The ribbon passes around the lower side of these wheels and the perforations 3 formed therein are engaged by the spurs. The wheels are positively driven which effects an accurate and constant feeding of the ribbon. The shafts 4 and 8 and spool 5 are journaled in the sides 11 of the frame and the cylinder is secured to semi-cylindrical lugs 12 forming part of the frame.

Beneath the cylinder is a system of punching needles 13 projecting from the ends of punching bars 14. The needles have their upper ends resting in holes 15 formed in the guide plates 16 in close proximity to the paper ribbon 1 passing above the plates. Holes 17 are formed through the bottom of the cylinder to register with the holes in the guide plates. This arrangement permits the punching needles as they are being raised by the operator at the keyboard (not shown) to pass through the paper ribbon traveling above them and to punch therefrom a small paper disk or nib. The movement of the punches is sufficient to bring their ends through the holes 17 in the cylinder to permit them to carry the paper nib punched from the ribbon in the chamber 7 and there deposit it. It does not take long before this chamber is sufficiently filled with nibs to require cleaning. My invention is devised purely to improve the manner of accomplishing this.

The chamber 7 is provided at the top with a large opening 18 and it is through this opening that my device operates to extract the nibs. They are removed almost instantaneously from the chamber to my device without any possibility of scattering the nibs.

about the machine. Moreover when using my nib extractor one person may be delegated to take it periodically to each machine in use and remove the nibs. The operator at the keyboard need not stop his work while this is being done.

A pipe or flexible hose in connection with a supply of compressed air is generally hanging near each machine. This is represented in the drawings by the fragmental piece of rubber tubing 19. The operator uses this hose for cleaning his machine from dust, stray paper nibs, etc., and a cock is provided for turning on or off the compressed air as desired. I make use of this hose and the compressed air for forcing the nibs from the chamber 7 into the receptacle of the extractor. It is on account of the availability of the compressed air and easily accessible tube that I make use of it as a means for removing the nibs. It is however equally possible to remove the nibs by reversing the operation and to use an air suction pipe to draw them into my receptacle instead of forcing them in by compressed air. Such a change however would require certain rearrangements and slight changes of the parts of my invention, which will later be pointed out. As just remarked, it is the availability of the compressed air already in use at the machines that makes it expedient to devise mechanism suitably adapted for its use. Should it subsequently be the custom to clean the machines by a suction of air instead of compressed air, it would then be necessary to change my extractor to make available the suction pipes.

My invention comprises a receptacle *a* for receiving the nibs. It may conveniently be a comparatively large vertical cylindrical sheet metal box open at the top. It has a ring *b* at the top for hanging it up when not in use to protect the parts at the base from injury. It is preferably large enough to hold the nibs from many machines so that it need not be emptied oftener than is reasonable. A cover *c* is provided for the box to securely retain the nibs therein. The nibs are forced into the box with the inrush of air, and it is necessary that the air should leave the box while the nibs are retained, therefore an outlet for the air is necessary. I prefer to make this in the cover as it will there be farthest away from the mass of collecting nibs gradually rising in the receptacle. I accordingly provide the cover with a large opening *d* and to prevent the escaping of the nibs I cover the hole with a fine wire mesh *e*. The cover preferably has a flange *f* for holding it on the box but other forms may be used. A tube *g* is secured through a hole in the bottom of the receptacle and is intended to afford communication between the chamber 7 and receptacle *a* in order to provide a passageway for con-

veying the nibs. It extends through the receptacle to a point near the top. This enables the nibs passing therefrom to gradually settle in the bottom of the receptacle without being unnecessarily agitated by the inrushing air. The tube extends sufficiently below the receptacle to raise it clear from the working parts of the machine and terminates in a plate *i* which is curved to cover the opening 18 to make a substantially air-tight fit.

The tube *g* should be closed when not in use to prevent any of the nibs in the receptacle from escaping therethrough. The closure may be made by a valve normally closed and only opened by the pressure of the air passing through the tube. Where the tube extends to a point near the top of the receptacle as in my preferred construction, it is desirable to use a continuously open tube when in position for use and a closed tube when out of position. I accordingly provide the following mechanism: Within the tube is secured a pair of sleeves *j* through which is passed a rod *k*. The rod extends the entire length of the tube and for a suitable distance below it. Its upper end is bent over and has secured thereon a disk *l* adapted to completely cover the top of the tube when the extractor is not in use. A helical spring *m* is mounted on the rod having its upper end secured to the rod and its lower end secured to the tube. The spring is under tension to continually hold the disk or cover down when not in use. The lower end of the rod is bent over and turned to form a ring *n*. This sets upon the shaft 8 when the extractor is in position for use to raise the cover *l* away from the mouth of the tube to continually leave the passage clear for the conveying of the nibs. The tube *g* preferably enters the plate *i*, forming the cover, at one end thereof. At the other end is an opening from which projects a tube *o*. This tube is the inlet for the compressed air and is of suitable size to freely permit its engagement with the end of the tubing 19.

It is essential that the opening 18 be completely covered when the nibs are being removed and as the size of this opening varies in different machines, I provide an adjustable cover to accommodate a variety of sizes of openings. The plate *i* is of a length to fit the smallest size opening. The adjustable means comprises a thin sheet metal frame *p* slidably mounted between the guides *q* secured to the bottom of the plate *i*. This auxiliary frame *p* is preferably stamped out in the center to form the frame comprising the side strips *r*, the rear strip *s* and the front *t* of a width to be sufficiently projected beyond the plate *i* to increase its length to completely cover the opening 18. The frame *p* being formed

open at the center permits an uninterrupted passage of the incoming air and provides admirable means for the arrangement of the guides *q*. These are secured within the 5 opening of the frame and comprise strips bent slightly out at their free edges *u* to engage the sides *r* on the inner sides thereof. Their inner ends are positioned to contact with the rear strip *s* to act as stops to 10 arrest the motion of the frame forward. To retain the frame normally in its foremost position a spring *v* is provided secured to the plate *i* as by eyelet *w* and at its other end to a hole in the strip *s*. This strip 15 instead of taking the upward curve of the frame is bent downward to afford convenient means for securing the spring thereto.

The operation of my extractor is as follows: When sufficient nibs have collected in 20 the chambers of the various machines, the person in charge takes the nib extractor to each machine. Without interfering with the operation of the machine, he places the plate *i* over the opening in the machine by 25 first tilting it to the left (Fig. 1) to bring the edge of the frame *p* against the end face *x* of the opening. He then forces the plate toward that face against the tension of the spring *v* until the opposite end of the plate 30 is in position to be dropped down to abut against the face *y* of the opening (or against the adjacent face of the lug 12). The spring *v* forces the plate and auxiliary frame apart and insures a complete covering of the opening 35 at the ends. On dropping the extractor in position the ring *n* contacts with the shaft 8 to effect an opening of the tube at the top. The positioning of the extractor as above described is accomplished by a single 40 movement and the person in charge need use only one hand which preferably grasps the device by means of the cylindrical receptacle. The other hand is free to grasp the rubber tubing 19 which is freely hanging 45 close to the machine. While positioning the extractor the rubber tube is at the same time carried to the tube *o* (the compressed air having been previously turned on). This is all done by practically one 50 operation, and ordinarily the rubber tubing need not be slipped over the tube *o* but only need meet it at the mouth. The air is allowed to pass through for a fraction of a minute, this being all that is necessary to 55 remove the nibs. The pipe is then dropped (the air being turned off) and my extractor pulled free from the machine by first slightly forcing it toward the end *x*. It is then ready to be carried to another machine.

60 If it is desired to use a suction of air instead of the compressed air, the tube *o* would then be inserted in the receptacle *a* instead of at the plate *i* and instead of the mesh covered opening *d* the mesh would be 65 placed over the said tube to prevent the pos-

sible drawing in of nibs. Moreover there should be an inlet for air in the chamber of the machine, preferably near the base thereof to agitate the nibs and carry them to the receptacle of the extractor.

Having thus described my invention I claim—

1. A portable device for extracting nibs from a nib receiving chamber of a ribbon perforating machine having an opening at 70 the top, comprising a receptacle for the extracted nibs, a plate for covering said chamber opening during the extracting operation, a tube secured to said plate and said receptacle affording communication between 75 the said chamber and said receptacle and a second tube secured to the said plate and in communication with the said chamber to permit a current of air to be passed through said chamber, said first tube and said receptacle to transfer the said nibs from the said chamber to the said receptacle.

2. A portable device for extracting nibs from a nib receiving chamber of a ribbon perforating machine having an opening at 80 the top, comprising a receptacle for the extracted nibs, a plate for covering said chamber opening during the extracting operation, a tube secured to said plate and said receptacle affording communication between 85 the said chamber and said receptacle, and means adapted for the use of pneumatic power for transferring the said nibs from the said chamber through the said tube and into the said receptacle.

3. A nib extractor for a ribbon perforating machine having a nib receiving chamber, comprising a receptacle for receiving the extracted nibs, a tube for connecting the said receptacle with the said chamber, a 105 cover for said tube, means for operating the said cover to close the said tube when the said extractor is removed from the said machine and to open the said tube when connected with the said machine, and means 110 adapted for the use of pneumatic power for transferring the said nibs from the said chamber through the said tube and into the said receptacle.

4. A nib extractor for a ribbon perforating machine having a nib receiving chamber open at the top and having a shaft passing therethrough, comprising a receptacle for receiving the extracted nibs, a tube for connecting the said receptacle with the said chamber through the said opening, a rod slidably mounted in said tube, a cover for said tube secured on the upper end of said rod, said rod being extended at its lower end to rest upon the said shaft when the extractor is in position for use to raise the said cover to open the said tube, a spring to return said cover to close said tube when the said extractor is removed from the machine and means adapted for the use of pneumatic 130

power for transferring the said nibs from the said chamber through the said tube and into the said receptacle.

5. A nib extractor for a ribbon perforating machine having a nib receiving chamber open at the top, comprising a receptacle for receiving the extracted nibs, a cover for said opening, a tube extending through said cover and said receptacle to afford communication between the said chamber and said receptacle, a cover for said tube, means for operating the said cover to close the said tube when the said extractor is removed from the said machine, and means adapted for the use of pneumatic power for transferring the said nibs from the said chamber through the said tube and into the said receptacle.

6. A nib extractor for a ribbon perforating machine having a nib receiving chamber open at the top and having a shaft passing therethrough, comprising a receptacle for receiving the extracted nibs, a cover for said opening, a tube extending through said cover and said receptacle to afford communication between the said chamber and said receptacle, a rod slidably mounted in said tube, a cover for said tube secured on the upper end of said rod, said rod being extended at its lower end to rest upon the said shaft when the extractor is in position for use to raise the said cover to open the said tube, a spring to return said cover to close said tube when the said extractor is removed from the machine and means adapted for the use of pneumatic power for transferring the said nibs from the said chamber through the said tube and into the said receptacle.

7. A nib extractor for a ribbon perforating machine having a nib receiving chamber open at the top, comprising an open receptacle for receiving the extracted nibs, a cover for said receptacle, a mesh covered air outlet in said receptacle, a cover for said chamber opening, a tube extending through said receptacle and said chamber cover to connect the said chamber with the said receptacle and a second tube through said chamber cover to convey compressed air through said chamber, said first tube and said receptacle to transfer the said nibs from the said chamber to the said receptacle.

8. A nib extractor for a ribbon perforating machine having a nib receiving chamber open at the top, comprising a receptacle for receiving the extracted nibs, an adjustable cover for said chamber opening, a tube extending through said cover and said receptacle for connecting said chamber with the said receptacle, and means adapted for the use of pneumatic power for transferring the said nibs from the said chamber through the said tube and into the said receptacle.

9. A nib extractor for a ribbon perforating machine having a nib receiving cham-

ber open at the top, comprising an open receptacle for receiving the extracted nibs, a cover for said receptacle, a mesh covered air outlet for said receptacle, an adjustable cover for said chamber opening, a tube extending through the said adjustable cover and receptacle affording communication between said chamber and receptacle, and a second tube extending through the said adjustable cover for connection with a supply pipe to convey compressed air through said chamber, said first tube and said receptacle for conveying the said nibs from the said chamber to the said receptacle.

10. A nib extractor for a ribbon perforating machine having a nib receiving chamber open at the top, comprising a receptacle for receiving the extracted nibs, an adjustable cover for said chamber opening, a tube extending through said cover and said receptacle for connecting said chamber with the said receptacle, a cover for said tube, means for operating the said cover to close the said tube when the said extractor is removed from said machine and to open the said tube when connected with the said machine, and means adapted for the use of pneumatic power for transferring the said nibs from the said chamber through the said tube and into the said receptacle.

11. A nib extractor for a ribbon perforating machine having a nib receiving chamber open at the top, comprising an open receptacle for receiving the extracted nibs, a cover for said receptacle, a mesh covered air outlet for said receptacle, an adjustable cover for said chamber opening, a tube extending through the said adjustable cover and receptacle affording communication between said chamber and receptacle, a cover for said tube, means for operating the said cover to close the said tube when the said extractor is removed from the said machine and to open the said tube when connected with the said machine, and means adapted for the use of pneumatic power for transferring the said nibs from the said chamber through the said tube and into the said receptacle.

12. A nib extractor for a ribbon perforating machine having a nib receiving chamber open at the top and having a shaft passing therethrough, comprising a receptacle for receiving the extracted nibs, an adjustable cover for said chamber opening, a tube extending through said cover and said receptacle for connecting said chamber with the said receptacle, a rod slidably mounted in said tube, a cover for said tube secured on the upper end of said rod, said rod being extended at its lower end to rest upon the said shaft, and means adapted for the use of pneumatic power for transferring the said nibs from the said chamber through the said tube and into the said receptacle.

13. A nib extractor for a ribbon perforat-

ing machine having a nib receiving chamber open at the top and having a shaft passing therethrough, comprising an open receptacle for receiving the extracted nibs, a cover for 5 said receptacle, a mesh covered air outlet for said receptacle, an adjustable cover for said chamber opening, a tube extending through the said adjustable cover and receptacle affording communication between said chamber and receptacle, a rod slidably mounted in said tube, a cover for said tube secured on the upper end of the said rod, said rod being extended at its lower end to rest upon the said shaft, and a second tube extending 10 through the said adjustable cover for connection with a supply pipe to convey compressed air through said chamber, said first tube and said receptacle for conveying the said nibs from the said chamber to the said 15 receptacle.

14. A nib extractor for a ribbon perforating machine having a nib receiving chamber open at the top, comprising a plate to partly cover said opening, an auxiliary plate slidably mounted on said first plate to cover the remainder of said opening, a tube extending upwardly through said first plate, a receptacle receiving the upper end of said tube, and means adapted for the use of pneumatic 25 power for transferring the said nibs from the said chamber through the said tube and into the said receptacle.

15. A nib extractor for a ribbon perforating machine having a nib receiving chamber open at the top, comprising a plate to partly cover said opening, an auxiliary plate slidably mounted on said first plate to cover the remainder of said opening, a tube extending upwardly through said first plate, an open 30 receptacle receiving the upper end of said tube, a cover for said receptacle, a mesh covered air outlet in said receptacle, a second tube through said plate to convey compressed air through said chamber, said first tube and said receptacle to transfer said nibs from the said chamber to the said receptacle.

16. A nib extractor for a ribbon perforating machine having a nib receiving chamber open at the top, comprising a plate to partly cover said opening, an auxiliary plate slidably mounted on said first plate to cover the remainder of said opening, a tube extending upwardly through said first plate, a cover for said tube, means for operating said cover to close the said tube when the said extractor is removed from the said machine and to open the said tube when connected with the said machine, a receptacle receiving the upper end of said tube, and means 55 adapted for the use of pneumatic power for transferring the said nibs from the said chamber through the said tube and into the said receptacle.

17. A nib extractor for a ribbon perforating machine having a nib receiving chamber

open at the top and having a shaft passing therethrough, comprising a plate to partly cover said opening, an auxiliary plate slidably mounted on said first plate to cover the remainder of said opening, a tube extending upwardly through said first plate, a rod slidably mounted in said tube, a cover for said tube secured on the upper end of said rod, said rod being extended at its lower end to rest upon the said shaft when the extractor is in position for use to raise the said cover to open the said tube, a receptacle receiving the upper end of said tube, and means adapted for the use of pneumatic power for transferring the said nibs 80 from the said chamber through the said tube and into the said receptacle.

18. A nib extractor for a ribbon perforating machine having a nib receiving chamber open at the top, comprising a plate to partly cover said opening, an auxiliary plate slidably mounted on said first plate to cover the remainder of said opening, a tube extending upwardly through said first plate, a cover for said tube, means for operating 85 said cover to close the said tube when the said extractor is removed from the said machine and to open the said tube when connected with the said machine, an open receptacle receiving the upper end of said tube, a second tube through said plate to convey compressed air through said chamber, said first tube and said receptacle to transfer the said nibs from the said chamber to the said receptacle.

19. A nib extractor for a ribbon perforating machine having a nib receiving chamber open at the top and having a shaft passing therethrough, comprising a plate to partly cover said opening, an auxiliary plate slidably mounted on said first plate to cover the remainder of said opening, a tube extending upwardly through said first plate, a rod slidably mounted in said tube, a cover for said tube secured on the upper end of said rod, said rod being extended at its lower end to rest upon the said shaft when the extractor is in position for use to raise said cover to open the said tube, an open receptacle receiving the upper end of said tube, a cover for said receptacle, a mesh covered air outlet in said receptacle, a second tube through said plate to convey compressed air through said chamber, said first tube and said receptacle to transfer the said nibs from the said chamber to the said receptacle.

20. A nib extractor for a ribbon perforating machine having a nib receiving chamber open at the top, comprising a plate to partly cover said opening, an auxiliary sliding plate secured to said first plate, guides secured to said first plate to slidably engage said auxiliary plate, a spring to retain said auxiliary plate in normal outward position,

a tube extending upwardly through said first plate, a receptacle for receiving the upper end of said tube, and means adapted for the use of pneumatic power for transferring 5 the said nibs from the said chamber through the said tube and into the said receptacle.

21. A nib extractor for a ribbon perforating machine having a nib receiving chamber open at the top and having a shaft passing 10 therethrough, comprising a plate to partly cover said chamber opening, an open frame slidably mounted beneath said plate to cover the remainder of said chamber opening, guides secured to said plate on the inside 15 of said frame opening to slidably engage said frame, a spring secured to said plate and to said frame within said frame opening to normally keep said frame in outward position, a tube extending through said

plate, sleeves secured in said tube, a rod 20 slidably mounted in said sleeves, a cover for said tube secured on the upper end of said rod, said rod being extended at its lower end to rest upon said shaft to raise said tube cover, a spring mounted on said rod to close 25 said cover when said extractor is removed from said machine, an open receptacle for receiving said tube, a cover for said receptacle, a mesh covered opening in said cover, a second tube through said plate to convey 30 compressed air through said chamber, said first tube and said receptacle to transfer the said nibs from the said chamber to the said receptacle.
